UNITED STATES PATENT OFFICE.

GEORGE M. WATERHOUSE, SR., OF NEW YORK, N. Y., ASSIGNOR OF ONE-HALF TO
GEORGE MEADE WATERHOUSE, JR., OF WILDWOOD, PENNSYLVANIA.

TROLLEY-CONTROLLING MECHANISM.

1,372,920.

Specification of Letters Patent. Patented Mar. 29, 1921.

Application filed December 5, 1918. Serial No. 265,410.

To all whom it may concern:

Be it known that I, GEORGE M. WATERHOUSE, Sr., a citizen of the United States, residing at 204 East 25th St., New York, in the county of New York and State of New York, have invented certain new and useful Improvements in Trolley-Controlling Mechanism, of which the following is a specification.

10 My present invention has relation to certain new and useful improvements in trolley controlling mechanisms of a type that may be advantageously employed in connection with a conventional form of apparatus for 15 retaining the trolley pole in a position whereby the wheel thereof is normally held in pressing engagement with the trolley wire; and as its primary object, it contemplates the provision of a novel device of this 20 character that includes means to be automatically actuated to return the trolley to a position whereby it may be quickly engaged with the wire and to automatically relieve the same from pressure when it is moved 25 into a folded position.

A further object of my invention is to provide a device of the type in question that is extremely simple in construction, strong and durable, and highly practical from both 30 the standpoint of the manufacturer and the standpoint of the user; and which, it is believed, may be manufactured at a comparatively low cost.

Various other objects and advantages will 35 become apparent during the continuance of the following description.

These objects are accomplished by such means as are shown in their preferred form in the accompanying drawings, described in 40 the following specification and then more specifically pointed out in the appended claims.

In the accompanying drawings wherein like characters designate like parts throughout the several views:

Figure 1 is a view in side elevation illustrating my invention as in its preferred embodiment and showing the same as used in conjunction with a conventional device for 50 retaining the trolley in pressing engagement with the respective wire;

Fig. 2 is a view in top plan illustrating the respective cylinders broken away so as to

disclose the interior mechanism thereof more clearly;

Fig. 3 is a view in cross section of an improved valve to be used in conjunction with my invention.

In Fig. 2 A denotes a suitable support which, in the present embodiment, is shown in the form of an ordinary car top, upon which the base or carrying blocks 10 and 11 respectively may be mounted. The base block 11 is provided with oppositely arranged bearings 12 that are designed to support a carrying shaft 13 upon which the trolley pole 14 may be mounted. In order to facilitate the more secure connection between the trolley pole and the shaft, the latter may be squared intermediate its ends as clearly shown in Fig. 2, while the trolley pole may be provided with a squared opening to receive the same. This construction is also clearly shown in Fig. 1. At its upper end, the trolley pole 14 is suitably forked or branched as at 15 to revolvably support the trolley wheel 16 as at 17, while the latter is designed to engage with an ordinary conductor 18. I have also shown the usual cable 19 for properly operating the trolley pole.

The conventional form of device for retaining the trolley pole or rather the wheel 16 thereof in pressing engagement with the conductor 18 at all times, as shown in the present embodiment, consists substantially of a cylinder 20 mounted on the base plate 10, the same being provided with a slidable piston 21 and an expansion spring 22 normally tending to retain the piston in its forwardmost position with respect to the cylinder. At its outer end, the piston 21 has pivotal connection with a head structure 23 as shown at 24, while the head structure is in turn cut away about its outer face as at 25, for engagement with a block 26 that is fixed on the carrying shaft 13 and equipped with suitable offsets 27 to seat in the said cut out portions. Thus it will be seen that the expansion spring 22 acting on the piston 100 will normally tend to retain the same in its forwardmost position with respect to the cylinder thus causing the engagement of the head 23 and the block 26 to the end that the shaft 13 will be moved so as to normally 105 retain the trolley pole in position shown in

dotted lines to the left in Fig. 1. Consequently, by drawing the pole downwardly and engaging the wheel 16 thereof with the conductor 18, it will be noted that the wheel 5 will be securely held in pressing engagement with the conductor. As set forth hereinbefore, my invention may be advantageously employed in connection with this type of device although it is to be understood that I 10 do not limit myself in any way to that specific application.

As in its present embodiment, my invention preferably consists of means whereby the trolley pole 14 may be automatically controlled and as a result operated both quickly and easily. To this end, I provide an air cylinder 28 that may be of any suitable construction or dimension, that carries a slideable piston head 29 and a piston rod 30; 20 the latter being slidably mounted exteriorly of the cylinder through the instrumentality of spaced bearings 31. An expansion spring 32 may also be arranged in the cylinder 28 so as to normally retain the piston head 29 25 in its rearwardmost position with respect thereto. In this embodiment the lower end of the trolley pole 14 is enlarged as at 33 to form a bearing face 34 for engagement with the abutment face 35 of the enlargement 36 30 of the piston rod at certain times and an actuating finger 37 for controlling the air valve such as will be hereinafter pointed out. Consequently, it will be seen that when the trolley pole assumes the position shown in 35 dotted lines to the left in Fig. 1, the engaging face 34 of the trolley pole will engage with the abutment face 35 of the piston rod 30 whereby actuation of the said piston rod 40 will cause the pole to be moved into a position similar to that shown in full lines in Fig. 1. However, this operation will be described at length hereinafter.

A suitable air line such as designated by the numeral 38 may be connected with the cylinder 28 as at 39 and controlled by a suitable three-way valve as shown in detail in Fig. 3. With a view of providing means for properly supporting the controlling valve and at the same time permit the free and 50 easy operation thereof, I employ a second shaft 40 which may also be carried by the bearings 12 as clearly shown in Fig. 1. While the valve proper, 41, is arranged to be movable with the shaft 40 its casing 42 55 is preferably arranged stationary with respect thereto, as in the usual construction. The air conducting pipes 43 and 44 respectively (see Fig. 3) have connection with the casing 42 at suitable points so as to register 60 with the openings 45 and 46. The valve 41 is in turn provided with a cut out 47 for establishing communication between the openings 45 and 46 at certain times and an aperture 48 which may be brought into registry with the outlet opening 49 of the cas-

ing at certain times while the cut out 47 is in registry with the opening 4. Consequently, when in the position shown in Fig. 3, air from the pipe 43 is permitted to flow through the valve into the pipe 44 and into 70 the cylinder 28. However, when the valve is moved into the position shown in dotted lines, communication with the pipe 43 will be closed and established between the pipe 44 and the outlet opening 49 of the valve 75 casing whereby the air from the cylinder may be exhausted.

I also provide novel means to automatically actuate the valve 41 simultaneously with movement of the trolley pole 14 to 80 such positions. With this in view, I equip the shaft 40 with an actuating member such as shown at 50 which in turn carries spaced studs 51 and 52 to lie in the path of movement of the finger 37 of the trolley pole. 85 Consequently, it will be seen that when the trolley pole moves into the left position shown in dotted lines in Fig. 1, the finger 37 thereof will be engaged with the stud 52 thereby causing movement of the actuating member 50 and the consequent movement of the shaft 40 and actuation of the valve 41. However, when the trolley pole is drawn into the other position shown in dotted lines, the shaft 40 will be moved in an opposite 90 direction, as will be the valve 41.

In the operation of my invention, as soon as the wheel 16 of the trolley pole is disengaged from the conductor 18, the trolley pole will be moved into a position such as 100 shown in dotted lines to the left in Fig. 1 by action of the expansion spring 22 and the conventional form of mechanism above referred to. By movement of the trolley pole to this position, however, the engaging face 105 34 of the enlargement 33 of the pole will be engaged with the abutment face 35 of the piston rod 30 and the finger 37 of the pole engages with the stud 52 of the actuating member 50 so as to rock the latter and cause 110 movement of the shaft 40 and the valve 41 to a position shown in full lines in Fig. 3. As soon as this operation occurs, air will be admitted through the valve 41 to the cylinder 28 thereby forcing the piston head 29 115 forwardly and causing the enlargement 36 of the piston rod 30 to move the trolley pole into a position such as shown in full lines in Fig. 1. When in this position the trolley pole may be quickly and easily manipulated so that the wheel 16 thereof may be engaged with the conductor 18. The valve 41 will of course remain open and the piston rod 30 will continue to bear against the enlargement 33 of the pole and act 120 against the tension of the expansion spring 22. However, when the operator draws the trolley pole into a folded position, such as shown in dotted lines to the right in Fig. 1, the finger 37 of the pole will be engaged 125 130

with the stud 51 of the actuating member thus moving the actuating member and the shaft 40 to cause movement of the valve 41 and thus establish communication between 5 the pipe 44 and the outlet opening 49. Thus the air from the cylinder 28 will be exhausted and pressure on the trolley pole released.

From the foregoing, it will be seen that 10 the advantages and novel features of my invention will be readily understood and, therefore, further detail description is deemed unnecessary.

In reducing my invention to practice I 15 find that the form referred to herein as the most practical and preferred embodiment is the most efficient, but realizing that certain conditions will necessarily vary in concurrence with the adoption of my device, I de- 20 sire to emphasize the fact that various minor changes in the details of construction and in the proportion of parts may be resorted to when required without sacrificing any of the advantages of my invention as defined 25 in the appended claims.

Having thus fully described my invention, what I claim as new and desire to secure by Letters Patent is:—

1. In a device of the character described, 30 the combination with a support, of a trolley pole, of a means to movably support said trolley pole, an actuating finger carried by said trolley pole, compressed air actuated mechanism arranged in proximity to said 35 trolley pole to be engaged therewith at certain times to move said trolley pole, a supporting member, a valve carried by said supporting member to control the admission of compressed air to said mechanism, an actuating member affixed to said supporting member, spaced studs on said actuating member, and said studs adapted to be engaged by said finger at certain times whereby said valve will be opened and closed, as and for 45 the purpose specified.

2. In a device of the character described, 50 the combination with a trolley pole, and means tending to retain the same in pressing engagement with a trolley wire, of a compressed air actuated mechanism to move the trolley pole against the tension of the said first mentioned means, a valve, an oscillatory actuating member therefor, and means carried by said actuating member to 55 be engaged at certain times by one end of the trolley pole upon movement of the pole in either direction for actuating said valve.

3. In a device of the character described, 60 the combination with a movable trolley pole including a wheel and means normally tending to retain said wheel in engagement with the trolley wire, of compressed air actuated mechanism to move the trolley pole against the tension of the said first mentioned means,

a shaft, a valve thereon, a casing surround- 65 ing the valve, means for conducting compressed air from the valve to said compressed air actuated mechanism, a valve actuating member secured to said shaft, and means carried by said valve actuating mem- 70 ber for engagement with one end of the trolley pole to actuate said valve when the end of the trolley pole engages said compressed air actuated mechanism.

4. In a device of the character described, 75 the combination of a movable trolley pole, means tending to retain the same in pressing engagement with a trolley wire, a compressed air actuated mechanism to move the trolley pole against the tension of the said 80 first mentioned means, a valve, and a valve operating member arranged in the path of movement of one end of the pole and normally disengaged therefrom, said valve operating member being adapted to be engaged 85 by the end of the pole upon movement of same in either direction.

5. In a device of the character described, 90 the combination of a movable trolley-pole having its lower end extended below the pivot thereof, means normally tending to retain the wheel of the trolley-pole in pressing engagement with a trolley wire, a compressed air actuated mechanism to move the trolley pole against the tension of the first 95 mentioned means, a valve for controlling the compressed air mechanism, and a valve actuating member arranged in the path of movement of the end of the trolley pole arranged below the pivot and adapted to be engaged 100 at certain times by the pole during movement of the same in either direction.

6. In a device of the character described, 105 the combination with a movable trolley-pole including a wheel, means normally tending to retain said wheel in engagement with the trolley wire, said trolley-pole having its lower end extending below the pivot thereof, a compressed air actuated mechanism to move the trolley pole against the tension of the first 110 mentioned means, said lower end of the trolley pole being provided with a bearing face, said compressed air mechanism including a plunger having an abutting face for engagement with the bearing face of the 115 pole, a valve for controlling the compressed air mechanism, a valve actuating member arranged in the path of movement of the end of the trolley-pole arranged below the pivot and adapted to be operated by the movement 120 of the pole in either direction.

7. In a device of the character described, 125 the combination of a trolley-pole having its lower end extending below the pivot thereof, means normally tending to retain said wheel in engagement with the trolley wire, a compressed air actuated mechanism to move the trolley-pole against the tension of

the first mentioned means, a valve for controlling the compressed air mechanism, a valve actuated member arranged in the path of movement of the end of the trolley pole 5 arranged below the pivot, and spaced studs on said valve actuating member adapted to be engaged by the lower end of the trolley-pole at certain times for actuating the valve

actuating member upon movement of the trolley-pole in either direction.

10

In testimony whereof I affix my signature in presence of two witnesses.
